UNITED STATES PATENT OFFICE.

DONALD J. MCKINNON, OF TORONTO, ONTARIO, CANADA, ASSIGNOR TO PACKARD MOTOR CAR COMPANY, OF DETROIT, MICHIGAN, A CORPORATION OF MICHIGAN.

INTERNAL-COMBUSTION ENGINE.

1,169,662.

Specification of Letters Patent.

Patented Jan. 25, 1916.

Original application filed October 16, 1909, Serial No. 522,909. Divided and this application filed September 8, 1913. Serial No. 788,693.

To all whom it may concern:

Be it known that I, DONALD J. MCKINNON, a subject of the King of Great Britain, and resident of Toronto, Ontario, Canada, have invented certain new and useful improvements in Internal-Combustion Engines, of which the following is a specification.

My invention relates to improvements in internal combustion engines, and this application is a division of my application, Serial No. 522,909, filed October 16, 1909.

One of the objects of the invention claimed in this application is to provide an internal combustion engine of simple and inexpensive but strong and durable construction, and in which sleeve valves are so arranged that they have extended bearing surfaces and are kept from heating, can be readily lubricated and easily repaired, and the friction and wear on the valves and their seats are reduced to a minimum and the engine is rendered more nearly silent in operation. These objects are attained by the embodiment of the invention herein shown and described, and in which the annular valve chamber is arranged entirely above the travel of the engine piston, is of smaller diameter than would be possible with such a chamber surrounding the piston portion of the cylinder, and surrounds the cylindrical head portion of the cylinder, the latter being water jacketed and entirely cutting off the valve chamber from the interior of the cylinder except through the inlet and exhaust and balancing ports.

The improvements are herein described and illustrated in the drawings as applied to an engine of the four cycle type, but the improvements are not necessarily restricted in application to this type of engine.

In the drawings, Figure 1 is a transverse sectional elevation of an internal combustion engine embodying the invention. Fig. 2 is a longitudinal sectional elevation thereof. Fig. 3 is a cross-section of the combustion chamber and valve on line 3-3, Fig. 1. Fig. 4 is a cross-section thereof on line 4-4, Fig. 2. Fig. 5 is a cross-section showing a valve of slightly modified construction. Fig. 6 is a side elevation, partly in section, of a multiple cylinder engine showing a different valve driving mechanism. Fig. 7 is a transverse sectional view of the motor

shown in Fig. 6, showing the valve and gear formed in one piece.

Like reference characters refer to like parts in the several figures.

A represents the cylinder, B the piston, C the crank shaft, c the pitman connecting the piston and crank shaft, and D the crank chamber, of a four-cycle internal combustion engine. These parts, with the exception of the cylinder, may be of any usual or suitable construction.

The cylinder A comprises a piston portion forming a piston chamber *a* in which the piston B reciprocates, and two cylindrical portions arranged concentrically above the piston portion, the inner cylindrical portion *H* constituting the cylinder head and preferably being provided with the combustion or compression chamber which is shown as relatively long and of smaller diameter than the piston chamber *a* and as located axially in line therewith. Said piston and inner portions are preferably water-jacketed as shown in the drawings and the inner portion has an integral end wall, also water-jacketed, and provided with a spark plug opening *H*¹ in the center thereof. The outer portion *H* of these concentric cylindrical portions may be stationarily secured on the piston portion in any suitable manner, for instance, this outer portion or casing and the piston portion are provided with abutting annular flanges *h*² which are secured together by bolts or other fastenings. The concentric cylindrical portions *H* and *H*¹ are separated from each other to form an annular valve chamber therebetween, the portion *H*¹ being provided with inlet and exhaust ports *E* and *F*, and the portion *H* with ports *E*¹ and *F*¹ which coöperate, respectively, with ports *E* and *F*. The portion *H* is provided with nipples or fittings *h* and *h*¹ which form continuations respectively of the ports *E* and *F*¹, for the attachment of suitable pipes for supplying the fuel to the cylinder and carrying off the exhaust gases.

As shown in the drawings the annular valve chamber is located entirely above the piston portion of the cylinder or above the travel of the piston and within said outer concentric portion *H* of the cylinder. By this arrangement of the valve chamber the outer diameter of the portion *H* may be

such that there is no substantial increase in the over-all diameter of a single cylinder or no increase in the length of a multiple cylinder engine due to the valve mechanism thereof. At the same time it is possible to have the sleeve valve of proper proportions to provide good port sizes and as shown in the drawings the inner diameter of the valve chamber or the outer wall of the head portion H' is contracted somewhat relative to the corresponding outer wall of the piston portion and is made only slightly greater than the bore of the piston portion, the proportions of the compression space and of the 10 water jacket of the portion H' being ample.

Arranged in the annular valve chamber, above described, and fitting the exterior of the inner cylindrical or head portion H' is a cylindrical or sleeve valve G which is provided with one or more ports g adapted to register in succession with the inlet and exhaust ports E, E', F, F', above described, in such manner as to admit the fuel to, and exhaust the burnt gases from, the cylinder 25 at the proper times with relation to the strokes of the piston.

In the construction shown in Figs. 1-4, the inlet and exhaust ports E and F are located with their centers in the same plane 30 and at a distance somewhat greater than ninety degrees apart, and the valve is provided with a single port g. Also in this construction the valve rotates continuously and as the engine illustrated is of the four-cycle type the valve is rotated by mechanism of any suitable construction, which revolves it once during every two revolutions of the crank shaft, or four strokes of the piston. The valve could, however, be made 35 with two or more ports, provided it is rotated so as to properly time the admission and exhaust. For instance, in the construction shown in Fig. 5, the valve G' is provided with two diametrically opposite ports 40 g' and is revolved once during every four revolutions of the crank shaft.

The valve G preferably has an end plate or wall with a central hole which is journaled to rotate on a hollow cylindrical boss 50 or stud g² which projects centrally from the integral end wall of the inner or head portion H'. The opening through this boss or stud forms a continuation of the spark plug opening H³.

55 The joints between the sleeve valve G and the concentric cylindrical portions H and H' can be packed in any suitable way to prevent leakage of the gases from the ports between these parts. As shown, packing 60 rings i are provided between the valve and the portion H' in grooves in the outer face of said portion surrounding the inlet and exhaust ports E and F, and other packing rings i' and i² are provided at the lower end 65 of the valve.

The valve is rotated by suitable mechanism which, in the single-cylinder engine shown in Figs. 1-4, consists of a shaft K journaled in bearings on the crank chamber D and the cylinder portion H and driven by 70 bevel gear wheels k from the crank shaft C and provided at one end with a gear pinion k² which meshes with a gear wheel k³ which is secured to or formed integral with the end of the valve. In Figs. 1 and 2 the gear 75 wheel k³ is removably secured to the valve G as by the bolts shown, while in Fig. 7 the gear wheel is an integral part of the valve.

L represents a flanged cover or end plate which is secured on the hollow stud g² by a 80 washer and nut l which is screwed on the threaded extremity of the stud. This cover incloses and protects the gear wheels k² and k³, and also serves in the construction shown to secure the valve on the stud g².

Fig. 6 shows a valve rotating mechanism of different construction applied to a multiple cylinder engine. The valves are constructed and arranged at the ends of the cylinders A in the manner explained above, 90 but the valves are provided with worm wheels m which mesh with worms m' on a shaft M which is journaled in suitable bearings on the outer portions H of the cylinders parallel with the crank shaft, the worm shaft being driven by a silent chain N, passing around chain wheels n n' on the crank shaft and worm shaft. Any other suitable mechanism for driving the valves, either in a single or a multiple cylinder engine, could 100 be employed.

As the interior surface of the sleeve valve is exposed at the inlet and exhaust ports E and F to the pressure in the combustion chamber during the compression and power 105 strokes of the piston, and as these ports are not opposite to each other, the pressure on the valve will be unbalanced unless provision is made to prevent this. The valve is preferably balanced by providing blind ports O 110 in the inner cylindrical portion H which ports are located at opposite sides of the plane of the inlet and exhaust ports and diametrically opposite to a line substantially midway between the inlet and exhaust 115 ports. These blind ports are made of suitable size for the pressure acting through them on the valve to substantially balance the pressure acting on the valve through the inlet and exhaust ports.

By the described construction and arrangement, the valve is located outside of the jacketed combustion chamber where it is kept at a substantially constant low temperature by the cooling fluid of the jacket, 120 which simplifies the problem of keeping the valve thoroughly lubricated and reduces the possibility of trouble due to differences in the expansion of different portions thereof. The valve is also easy of access for repair- 130

ing it and as it is balanced and rotates continuously in the same direction on the extended bearing surface afforded by the external face of the inner cylindrical portion 5 H', the friction and wear are reduced to a minimum and the valve is practically noiseless in operation.

Having described my invention what I claim and desire to secure by Letters-Pat-
10 ent is,

1. In a multiple cylinder internal combustion engine, the combination of a plurality of cylinders side by side, a rotary valve in each of said cylinders and having worm gear teeth formed on its periphery and integral therewith, a valve operating shaft arranged longitudinally of the engine parallel with the engine crank shaft and having worms in mesh with said worm gear teeth and adapted to rotate the several valves simultaneously, bearing for said shaft in an upward extension of said cylinders and positive driving connections from the engine crank shaft to said valve shaft.
2. In an internal combustion engine, the combination of a cylinder having spaced inner and outer walls forming an annular valve chamber, a rotary sleeve valve in said chamber and having gear teeth formed on its periphery thereof and integral therewith and positive driving connections from the engine crank shaft to said gear teeth.
3. In an internal combustion engine, the combination of a cylinder having inner and

outer walls forming an annular valve chamber, a rotary sleeve valve in said chamber having worm gear teeth on its periphery at one end thereof, a valve operating shaft arranged parallel with the engine crank shaft and having worms in mesh with the said 40 teeth, bearings for said shaft in an upward extension of said cylinder and positive driving connections from the engine crank shaft to said valve shaft.

4. In a multiple cylinder internal com-
bustion engine, the combination of a plural-
ity of cylinders side by side, a rotary valve
in each of said cylinders and having worm
gear teeth directly thereon, a valve operat-
ing shaft arranged longitudinally of the en-
gine parallel with the engine crank shaft
and having worms in mesh with said worm
gear teeth and adapted to rotate the several
valves simultaneously, bearings for said
shaft in an upward extension of said cylin-
ders, chain wheels arranged on the engine
crank shaft and said valve shaft respec-
tively, at the fly wheel end of the engine,
and chain connections between said chain
wheels for driving the valve shaft from the 60
crank shaft.

In testimony whereof I affix my signature
in presence of two witnesses.

DONALD J. McKINNON.

E. P. HALL.

It is hereby certified that in Letters Patent No. 1,169,662, granted January 25, 1916, upon the application of Donald J. McKinnon, of Toronto, Ontario, Canada, for an improvement in "Internal-Combustion Engines," errors appear in the printed specification requiring correction as follows: Page 3, line 21, claim 1, for the word "bearing" read *bearings*; same page, line 30, claim 2, for the word "its" read *the*; and that the said Letters Patent should be read with these corrections therein that the same may conform to the record of the case in the Patent Office.

Signed and sealed this 22d day of February, A. D., 1916.
